UNITED STATES PATENT OFFICE.

FRANKLIN M. REED, OF INDIANAPOLIS, INDIANA, ASSIGNOR TO THE SECTIONAL GRAIN DOOR COMPANY, EXISTING UNDER THE LAWS OF INDIANA.

SECTIONAL GRAIN-DOOR.

No. 910,020.

Specification of Letters Patent.

Patented Jan. 19, 1909.

Application filed May 1, 1907. Serial No. 371,362.

To all whom it may concern:

Be it known that I, FRANKLIN M. REED, a citizen of the United States, residing at Indianapolis, in the county of Marion and State of Indiana, have invented certain new and useful Improvements in Sectional Grain-Doors, of which the following is a specification, reference being had therein to the accompanying drawing.

10 My invention relates to certain improvements in sectional grain-doors for railroad freight cars, as hereinafter described and particularly pointed out in the claims.

The object of this invention is to produce 15 a door structure of such a character that one or more of the sections thereof may be used as required; to provide means whereby each of the sections may be independently locked in closed position as well as in open position; 20 to provide means whereby each of said door sections are rendered non-removable and non-detachable from the car to which said door structure is applied; to provide means whereby each of said door sections will be 25 prevented from moving in a longitudinal direction to eliminate a rattling of the door sections; and, finally, to produce a structure whereby the sections of the door may be telescoped or moved longitudinally into an in- 30 closing casing, which may be a part of the structure of the car; whereby the door sections are concealed and carefully stored when not in use. I attain these objects by 35 means of the construction of the sectional grain door illustrated in the accompanying drawings in which like numerals of reference designate like parts throughout the several views.

Figure 1 is a longitudinal sectional elevational view of a box car showing my invention of a sectional grain door applied to the same. Fig. 2 is a sectional top view of the same taken along the line A. B. in Figs. 1 and 3. Fig. 3 is a sectional end view of the same taken along the line C. D. in Figs. 1 and 2. Fig. 4 is an enlarged detail broken view of a door section. Fig. 5 is an enlarged detail broken view of a portion of the lower door section showing the auxiliary grain door thereof. Fig. 6 is a transverse sectional view of the same taken along the line E. F. in Figs. 1 and 5. Fig. 7 is an enlarged detail broken view of a portion of a door post showing the 55 gravity latch and a door section engaged

by said latch to retain said door section in closed position. Fig. 8 is an enlarged detail broken sectional top view of the door post and a portion of a door section and a portion of its inclosing chamber said section taken along the line G. H. in Figs. 1, 3, and 7; and, Fig. 9 is a similar view showing a door section locked in its concealed position in its inclosing chamber.

The car to which my invention of a sectional grain door may be applied may be of the usual type of closed or box freight car having the sides 1, in which are formed the door openings 2, and the floor 3 supported by a suitable framework 4.

Situated at one side of the door opening 2 is a door receiving chamber 5, into which the door sections 6, 7, 8, and 9 are adapted to be slid to be concealed. The chamber 5 is inclosed by the jamb or vertically extending stop post 10, the horizontally extending rail 11, the end vertically extending closing rail 12, and the inclosing casing 13. The chamber 5 is divided into longitudinally extending portions or compartments 14, 15, 16 and 17 by the horizontally extending strips or bars 18, 19, and 20, and in each of said compartments is adapted to be slid or telescoped its particular door section. The strips or bars 18, 19 and 20 do not extend the entire length of the compartment, but are shorter than said compartment to provide a space between their ends and the end post 12, for the purpose of permitting grain, seed, or other finely divided matter which might be deposited on said strips or bars from accumulating thereon to retard or prevent the proper closing of the door sections. The door-sections when moved backwardly into their respective compartments will push any small obstruction or accumulation of fine matter that may be deposited on said strips or bars along said bars to their inner ends which ends being situated so as to leave a clearing space between them and the post 12 as hereinbefore described, will permit said matter to drop from said strips to the bottom of the compartment from whence it is removed through a suitable clearing opening formed in the bottom of the compartment casing by the backward movement of the lower door section when the latter is moved backwardly into the position shown in Fig. 1. The said strips or bars each operate as distance pieces which fit in between the

casing of the car and the inclosing casing of the compartment, thereby reinforcing said compartment casing against any pressure from within the car, as that produced by grain or loose matter with which the car may be loaded, and thus preventing said casing springing inwardly against a door section or the door-sections and preventing their movement either inwardly or outwardly. The door sections 6, 7, 8, and 9 are each provided with longitudinally extending rabbeted edges, so that when said door sections are situated in their superposed positions said sections will lap at their longitudinal edges and thereby form close joints at said contacting edges and prevent a leakage of the grain. The floor 3 is provided with a groove which is situated to extend along the bottom of the chamber 5, along and adjacent to the door opening 2 to the door post 24. In this groove a channel iron 6^a of suitable size and length to completely fill said groove is fitted and secured therein to form a substantial guide way in which the lower door section 6 is adapted to slide in a longitudinal direction. At or near the ends of said door sections 6, 7, 8, and 9 and on the inner sides thereof are secured the channel irons 21 and 22 which operate as stops to prevent the door section from being either forcibly moved too far into or withdrawn from its inclosing chamber and detached and removed from the car. The channel iron 21 is situated in such position at or near the outer end of a section that it will contact the stop post 10 when a door section is slid or telescoped into its compartment and said channel iron stops prevent said door section from being moved too far into said compartment to injure the pointed inner end thereof by contacting with the end post 12 of said inclosing chamber.

The inner end channel irons 22 of the door sections are situated on the opposite ends and 45 on the same side of each of said door sections as the channel irons 21 and said channel irons are so situated as to permit any one of the door sections to be independently moved longitudinally out of its compartment not only to extend over the door openings 2, but also to permit a door section to be slid longitudinally till its projecting end enters the space situated between the inside of the car and the vertically extending door 55 lip 23 secured on the vertically extending distance-bar 24 whereby this end of a section is securely retained and supported against the side posts of the door opening 2. The opposite ends of the door sections 6, 7, 8, 60 and 9, are formed with inclined or beveled portions 25 which are so arranged that when a door section is moved longitudinally its full extent said door section will slide off its supporting strip and its under edge will 65 rest upon the upper edge of the next under-

lying section and the beveled end portion 25 of said section will wedge against the correspondingly formed end 26 of the supporting strip and each of said door sections has its inner end portion thus formed so that 70 the entire series of door sections, when all are used, will be secured firmly and tightly in place and a longitudinal movement of any of said sections is prevented, and therefore all noise and rattle of said door sections 75 is eliminated.

The beveled or inclined ends 25 formed on said door-sections operate as a means for elevating or raising this end of each of the door sections to the level of its supporting 80 strip or bar so as to be readily moved longitudinally or telescoped into its compartment.

The door lip 23 is secured to the post 24 by the securing bolts 36 which are spaced at regular intervals apart corresponding to the 85 depth of each door-section, which bolts also serve the purpose of a support or rest upon which this end of each door-section rests. The three upper door-sections 7, 8, and 9, being thus supported at both their ends, the 90 weight of that section upon the contiguous section or that section situated directly below and under it is either eliminated wholly or in part, and thus relieves the lower section 6 of the weight of the upper superposed 95 sections 7, 8, and 9, so that said lower section may be readily moved independently of said upper sections to remove grain or other loose matter with which the car may be loaded and thereby release said upper 100 sections of all outward pressure to permit their opening.

The next important feature of this invention consists in the means whereby the doors are locked when each of the door-sections are moved into position to close the door opening 2 and the means for locking said door-sections when moved into their inclosing compartments.

The door post 27 is provided with a series 110 of open recesses 28 in each of which is pivotally secured a gravity operated latch 29, each of which is situated so as to drop or swing into engagement with its door section, or said latch is adapted to swing downwardly 115 to be situated transversely over the end of a door section to maintain and lock the same in position.

The gravity latch 29 is constructed with its engaging end made larger and weightier 120 than the trigger end so that the pivotal center is situated to one side of the center of gravity of the latch which center of gravity is situated between said pivotal center and the engaging end of said latch so that said 125 latch will fall automatically into engagement with its door-section whether the latter is open or closed.

Each of the door sections 7, 8, and 9 is provided with a latch engaging groove 30 130

which is adapted to be engaged by a latch 29 when a door section is slid to extend out of its inclosing compartment its full extent or till said door section is extended till a 5 groove 30 falls in the plane of the swing of a latch 29, thus each of said door sections is doubly secured in its relative positions.

Each of the latches 29 is arranged in such position, relatively to its engaging groove 30, so that when a door section tends to move or does move slightly vertically or upwardly, the rounded end portion of said groove 30 will assume a position eccentric with the pivotal center of its latch 29, thereby causing the rounded end portion of said groove to contact with the end of said latch to wedge or jam that door section to securely hold the latter and prevent it from rattling or rising sufficiently far to permit the grain in 20 the car escaping through the longitudinal joints of the door sections.

It is generally necessary to tap a grain car before it is possible to open a side door of a car on account of the great pressure of the 25 grain against the inside of the door, I provide, for this purpose, an auxiliary hinged door 31 which is secured to swing automatically in a door opening 32 formed in the lower broader door section 6 and said door 31 is provided with a latch 33 which is secured to said door by the rivets 34 which pass through the slot 35 formed in said door to the cover strip 37 situated on the exterior side of the door, (see Fig. 6), and by which 30 cover strip the latch 33 is raised to release the door. The said slot in said door is of such a length as to permit the latch 33 to be moved longitudinally sufficiently far to release said auxiliary door to permit it to 35 be opened, whereby said auxiliary door may be unlocked and opened from the exterior of the car.

It will be particularly noted that the auxiliary swinging door is secured in the 40 door opening 32 of the lower door section 6 by suitable hinges secured to the top edge of said door opening to swing outwardly so that the pressure of the grain within the car 45 will operate to open said door when said door latch is released.

I claim:—

1. In a sectional door for grain cars, the combination with a plurality of superposed

longitudinally slidable door-sections, each provided with longitudinally extending lap- 55 ping edges, inclined or beveled inner end bearing portions, an inclosing chamber, strips extending longitudinally thereof and terminating near the inner end of said chamber and arranged at their outer ends to extend sufficiently toward the open end of said chamber to contact the inclined end of said door-sections when the latter are in closed position, of a door-bar, a door-bar lip, securing bolts extending through said door-bar-lip and arranged at intervals apart corresponding to the depth of each of said door-sections, said door-sections adapted to be supported at their inner contacting beveled ends on the outer contacting beveled ends of 60 said strips and at their outer ends on said door-bar lip securing bolts.

2. In a sectional door for grain cars, the combination with a plurality of superposed longitudinally - slidable door. sections, in- 75 clined or beveled end bearing portions on said sections, and a door section inclosing chamber, of a series of longitudinally ex- 80 tends strips dividing said chamber into door section receiving partitions, and a bevel- 85 ed or inclined bearing end portion on each of said supporting strips, and each of said strips in said series arranged to extend progressively to contact the inclined end of the section to be supported.

3. In a sectional door for grain cars, the combination with a plurality of superposed longitudinally slidable door-sections, a door inclosing chamber, longitudinally extending strips dividing said chamber into door-section receiving compartments wherein said door sections are telescoped, of gravity latches situated to swing transversely of each of said sections, each having its pivotal point situated at a point intermediate its 90 longer and smaller or trigger ends so that said latch will drop automatically into engagement with a door - section to lock the 95 same and prevent it from rising.

In testimony whereof I affix my signature 100 in presence of two witnesses.

FRANKLIN M. REED.
